UNITED STATES PATENT OFFICE.

MAXIMILIEN GOLDBERGER, OF PARIS, FRANCE.

EXPLOSIVE-ENGINE.

1,101,737.

Specification of Letters Patent. Patented June 30, 1914.

Application filed November 15, 1910. Serial No. 592,579.

To all whom it may concern:

Be it known that I, MAXIMILIEN GOLDBERGER, a subject of the Empérator of Austria-Hungary, residing at Paris, France, have 5 invented certain new and useful Improvements in Explosive-Engines, of which the following is a full, clear, and exact specification.

The present invention relates to improvements in explosive engines, especially to engines adapted for aviation purposes.

The explosive engines according to the present invention differ from the engines heretofore devised for the above purpose by 15 the arrangement of stationary pistons and movable cylinders. The machine is perfectly balanced and while its working parts are as strong as those of an automobile engine, it is of extremely light weight because 20 all superfluous parts have been omitted so that the machine can easily be started and is well balanced, the working parts of which allow of a convenient and ready inspection, starting, etc.

25 To enable others to understand my invention, reference is had to the accompanying drawings, in which:

Figure 1 is a longitudinal elevation partly in section of the machine according to the 30 present invention. Fig. 2 is a cross-section on line A—A of Fig. 1. Fig. 3 is a plan view of a piston.

The motor is arranged in a frame-work composed of two parts, an upper one 2 and 35 a lower one 3 strongly reinforced by uprights 4.

The upper part 2 of the frame carries the journal boxes 5, 6 of the motor shaft 13 and is fitted with the clamping lugs 7, 7 on 40 the front and on the rear so as to be attached to the frame of the flying machine.

On the lower part 3 of the frame the stationary pistons 10 are secured by bolts or the like. Upon these stationary pistons 10 45 the cylinders slide and transmit the explosive force to the engine shaft by means of the crank shafts 9.

On account of the reciprocatory movement and the peculiar helical form of the ribs 50 the cylinders 12 are rapidly cooled while the ribs do not offer any perceptible resistance to the motion of the cylinders and thus do not produce any braking effect upon the motor.

The helical ribs as shown, permit a more 55 rapid cooling of the cylinders than horizontally disposed ribs would, which would allow the formation of an air cushion between them. Moreover, horizontal ribs will 60 present a much greater resistance to the motion of the cylinders. While vertical ribs would increase the cooling effect, they would not reinforce the cylinder as well as helical ribs do. The construction of the ribs as 65 helical ones therefore produces the following good results:

The air surrounding the cylinder and cooling it is constantly renewed, and the ribs present the least possible resistance to the operation of the cylinder and thus do not 70 produce any braking effect upon the motor. The cooling of the cylinders is effected by the current of air created by the fly-wheel, which current traverses the mantle of the motor provided with perforations at its 75 lower part.

The feed valves 15 for the supply of the explosive mixture to the cylinders 12 are situated in the piston 10 and thus inclosed, it will be seen that they can easily be removed by detaching the pitman 9 from the wrist pin 18 and lifting the cylinder 12. Each of these stationary pistons as shown 80 in Figs. 2 and 3 comprises a channel 16 for the carbureted gases connected by a tube 85 14 with the carburetor, and an exhaust 17 controlled by the valve 15 during the operation of the movable cylinder.

The cylinders 12 carry at their extreme 90 end the wrist pin 18 of the base of the connecting rod. The crank shaft 13 running in the boxes 5, 6 is not subject to torsion usually caused by the vibrations of the mass of the fly-wheel 19 during its starting and running periods, as the fly-wheel is not fixedly secured directly to the shaft, but by the intermediary of a roller ball-bearing 20 on the box 6 and the impulse is given by a yielding dog 21 keyed to the driving shaft. The hub of the dog 21 carries the coupling 100 plate 22 for the propeller or for a reducing gear. This original method has the effect of relieving entirely the driving shaft of the weight of the fly-wheel and of allowing the said fly-wheel to automatically balance itself on its axis, the roller bearing 20 greatly relieves the rear journal 6 of the direct influence of the weight of the fly-wheel. 105

The lower part 3 of the frame provides suitable bearings 23, 24 for the shaft 25 which is actuated by cams or other suitable means for the operation of the suction and 5 exhaust valves.

In order to allow a starting of the motor by other means than by the propeller, a crank handle 31 has been provided, however its use is optional and when done away with, 10 the magneto 30 may be keyed to the end of the shaft. The oil distribution is insured by the tank 32 installed at the highest point of the engine and constituting a gravity lubrication device with regulation feed oil 15 cups.

I claim:—

1. An explosive engine for aviation purposes comprising in combination, a frame composed of connected upper and lower 20 members, the upper of which supports a crank shaft, journal boxes on the upper member at the ends of said shaft, a flywheel rotating on ball-bearings upon one of said boxes, a stationary piston secured to the 25 lower member of the frame, and a cylinder

secured to said crank shaft by a rod and reciprocating on said stationary piston.

2. An explosive engine for aviation purposes comprising in combination, a frame composed of connected upper and lower 30 members, the upper of which supports a crank shaft, journal boxes on the upper member at the ends of said shaft, a flywheel rotating on ball-bearings upon one of said boxes, a stationary piston secured to 35 the lower member of the frame, a cylinder secured to said crank shaft by a rod and reciprocating on said stationary piston, heat radiating ribs spirally arranged on said cylinder, means for supplying explosive 40 mixture to said piston and means for controlling the admission of the explosive mixture to said cylinder for reciprocation upon said piston, substantially as described.

In witness whereof I have hereunto set my hand in the presence of two witnesses.

MAXIMILIEN GOLDBERGER.
